(57) **CLAIM**

The ornamental design for an electric lap robe, as shown and described.

DESCRIPTION

FIG. 1 is a front elevation view of an electric lap robe showing our new design;

FIG. 2 is a rear elevation view thereof;

FIG. 3 is a right side view thereof;

FIG. 4 is a left side view thereof;

FIG. 5 is a top plan view thereof;

FIG. 6 is a bottom plan view thereof;

FIG. 7 is a referential rear elevation view thereof showing a state with a flap being turn over;

FIG. 8 is a referential view thereof showing a state with a controller being connected and bound by the flap; and,

FIG. 9 is a referential view thereof showing a state folded and fastened by a band.

The broken lines shown in FIG. 4 are for environmental purposes only and form no part of the claimed invention, and the controller and code thereof in FIG. 8 shown in broken lines and the band in FIG. 9 shown in broken lines form no part of the claimed design.
